UNITED STATES PATENT OFFICE.

PERRY A. DE GARMO, OF STRATTON, NEBRASKA.

SUBPACKING-RING FOR DISKS.

1,264,025.

Specification of Letters Patent. Patented Apr. 23, 1918.

Application filed September 28, 1916. Serial No. 122,682.

To all whom it may concern:

Be it known that I, PERRY A. DE GARMO, a citizen of the United States, residing at Stratton, in the county of Hitchcock, State 5 of Nebraska, have invented a new and useful Subpacking-Ring for Disks; and I do hereby declare the following to be a full, clear, and exact description of the invention, such as will enable others skilled in the art to which it appertains to make and use the same.

The present invention relates to a subpacking ring attachment for disks, and has for its object to provide a device of this character which embodies novel features of 15 construction whereby it can be readily applied to a disk, thereby enabling the disk to answer the purpose of two farm implements.

Further objects of the invention are to provide an attachment of this character 20 which is comparatively simple and inexpensive in its construction, which can be readily applied to the disk or removed therefrom, which will not bend or injure the edge of the disk in any manner, and which eliminates the necessity of having two independent farm implements.

With these and other objects in view, the invention consists in certain novel combinations and arrangements of the parts as will 30 more fully appear as the description proceeds, the novel features thereof being pointed out in the appended claim.

For a full understanding of the invention, reference is to be had to the following description and accompanying drawing, in 35 which:—

Figure 1 is a side elevation of a disk provided with a sub-packing ring attachment constructed in accordance with the invention, one of the segmental sections of the 40 attachment being indicated by dotted lines as swung outwardly away from the disk.

Fig. 2 is a transverse sectional view through the disk with the attachment 45 thereon.

Fig. 3 is an edge view of the same, portions being broken away and shown in section to illustrate more clearly the hinged connection between the segmental sections of 50 the attachment.

Fig. 4 is a similar view, looking at the device from the opposite edge, and showing the clamping screw for drawing the segmental sections into operative position.

Fig. 5 is a transverse sectional view

through a portion of the attachment, showing a slight modification.

Fig. 6 is a similar view, showing a still further modification.

Corresponding and like parts are referred to in the following description and indicated in all the views of the drawings by the same reference characters.

Referring to the drawings, which illustrate one embodiment of the invention, the 60 numeral 1 designates a disk which is of the conventional shape and configuration, being concave on one side and convex on the opposite side. The sub-packing ring is formed in a series of complementary and 70 interchangeable segmental sections 2 which are adapted to be applied to the edge of the disk and clamped in position thereon. In the present instance there are two of the sections 2, each of which is semi-circular in 75 shape, although the exact number of the segmental sections which may be employed is not material to the invention. These segmental sections 2 are connected at one end by a hinge plate 3, said ends being slit 80 longitudinally at 4 to receive the hinge plate 3 which is engaged by the pivot pins 5. It will also be observed that the hinged ends of the sections 2 have the outer corners thereof rounded at 6 so that the sections can 85 be readily swung apart when applying the attachment to a disk or removing it therefrom. Any suitable clamping means may be provided for detachably connecting the 90 free ends of the segmental sections 2. In the present instance one of the sections carries a clamping screw 7 which has the head thereof exposed within a notch 8 in the periphery of the section, the threaded end of the screw being adapted to engage the opposite segmental section, so that by tightening the screw the two sections can be drawn 95 securely together.

The inner faces of the segmental sections 2 are grooved at 9 to receive the edges of the 100 disk 1, inwardly projecting flanges 10 and 11 being provided upon opposite sides of the said groove. The outside flange 10 is considerably wider than the inside flange 11, and has the inner face thereof beveled at 10^a 105 so that it will fit squarely against the convex outer face of the disk 1 and obtain a firm bearing thereon. The inside flange 11 is shorter than the outside flange 10, and is designed to be arranged on the concave side 110

of the disk. Owing to the fact that the outside flanges 10 of the segmental sections 2 have an appreciable width and are inclined to obtain a firm bearing upon the convex outer side of the disk 1, the edges of the disk are relieved of the load, and the attachment can be used without danger of bending or injuring the edges of the disk.

The outer periphery of the packing ring attachment may have any desired configuration. In Fig. 1 the outer edge is substantially semi-circular in cross section, although this outer edge may have a V-shaped cross section, as indicated by Fig. 5, or a square cross section, as indicated by Fig. 6.

When the attachment is clamped in position upon the disk, the device can be used as a sub-packing ring, and by the use of this attachment the necessity of providing a separate implement is avoided, since the one implement can be used for both purposes. Where a larger number of segmental sections is used, these sections may be detachably connected, to admit of the device being readily fitted upon large or small disks.

A slight modification is shown by Fig. 6, in which a filling strip 12 is provided for obtaining a tight engagement with the disk

in the event the latter should have become slightly worn by much use, so that the packing ring attachment would otherwise be loose thereon. This filling strip 12 may fit against the beveled inner faces 10^a of the outside flanges 10, and the outer edge thereof may be returned at 12^a to fit around the edge of the disk 1. Proper compensation will thus be made for wear, and the device can be tightly clamped upon the worn disk.

Having thus described the invention, what I claim as new and desire to secure by Letters Patent, is:—

The combination with a disk, of a sub-packing ring formed in a series of segmental sections formed upon their inner faces with V-shaped grooves to receive the edges of the disk, and a removable V-shaped filling strip inserted between the edges of the disk and the base of the groove to compensate for wear of the disk.

In testimony whereof I have signed my name to this specification in the presence of two subscribing witnesses.

PERRY A. DE GARMO.
